HEATER FOR AUTOMOBILES

Filed Nov. 21, 1921

2 Sheets-Sheet 2

UNITED STATES PATENT OFFICE.

TOM J. SCOTT, OF CINCINNATI, OHIO.

HEATER FOR AUTOMOBILES.

Application filed November 21, 1921. Serial No. 516,594.

To all whom it may concern:

Be it known that I, TOM J. SCOTT, a citizen of the United States, residing at Cincinnati, in the county of Hamilton and State of Ohio, have invented certain new and useful Improvements in Heaters for Automobiles, of which the following is a specification.

It is the object of my invention to provide a new and improved heater of substantial construction for automobiles and so arranged that the escape of fumes into the inside of the automobile is precluded; to provide an interior arrangement for the heating element whereby the same acts as a cushion for the combustion-discharge to avoid percussive noise in the interior of the automobile; to provide novel means whereby the device may be applied to exhaust-pipes of various diameters; to provide novel means whereby the operation may be had from either side of the exhaust-pipe; and to provide novel adjustable clamping means for attaching the device to automobiles.

My invention is applicable to touring cars, roadsters and closed cars, as well as trucks and tractors, and other vehicles driven by internal combustion engines, and may be applied at any suitable point or points in the floor of the automobile. I have shown the same applied at the foot-space in front of the rear seat of a touring car, it being assumed that the car is supplied with a proper top and side and rear curtains, not shown because well-known.

The invention will be further readily understood from the following description and claims, and from the drawings, in which latter:

Fig. 1 is a side elevation of an automobile, partly broken away, showing my improved device applied thereto.

Fig. 2 is a plan view of my improved device.

Fig. 3 is a side elevation of the same, partly broken away.

Fig. 4 is a front end elevation of the same.

Fig. 5 is a rear end elevation of the clamping means.

Fig. 6 is a cross-section of the same, taken on the line 6—6 of Fig. 3, showing the same arranged for clamping about an exhaust-pipe of larger diameter and having the operating arm at one side, in full lines, and showing the same clamped about an exhaust-pipe of smaller diameter and with the op-

erating arm at the other side of the same, in dotted lines.

Fig. 7 is a plan view of the body section of the heating element.

Fig. 8 is a cross-section of the heating element, taken on the line 8—8 of Fig. 7.

Fig. 9 is a cross-section of the same, taken on the line 9—9 of Fig. 2.

Fig. 10 is a transverse section of the valve-operating means, taken on the line 10—10 of Fig. 11.

Fig. 11 is a longitudinal axial section of the same, taken on the line 11—11 of Fig. 10.

Fig. 12 is a vertical axial section of a portion of the exhaust pipe and its valve; and

Fig. 13 is a horizontal axial section of the same.

21 represents the usual exhaust-pipe of the automobile, and 22 is the muffler. An opening 23 is provided in this exhaust-pipe. 24 is a pivoted valve, arranged to normally close this opening. The valve is pivoted on a stem 25 journaled in bearing-holes 26 located in the respective sides 27 of a clamp 28.

This clamp is formed of two mating sides struck up out of sheet-metal. Each side comprises an arcuate apron-side 31, a wall-section 32 of a passage 33, a web 34 connecting said wall-section and apron-side, and a flange 35 above said wall-section. The wall-sections are at an angle to the arcuate sides. The portion of the side above the apron-side forms a rigid structure by reason of the manner in which the sheet-metal is formed, while flexure of the apron-side is permitted to change its arc of curvature to correspond to exhaust-pipes of different diameters.

The passage 33 communicates by means of the valve 24 with the opening 23 in the exhaust-pipe. A communicating pipe, shown as a flexible pipe 38, connects with the passage 33 and is arranged to be secured to the walls of said passage by means of a cotter-pin 39. The flexible pipe 38 communicates with the heating element 40.

The valve-stem has an extended shank 43. An operating arm 45 is fixed to the extended shank and is normally retracted to close the valve by means of a spring 46. An operating link 47 connects with the operating arm. This operating link is of a flexible comparatively stiff wire and operates longitudinally in a flexible guide 48, made for instance of

spirally wound wire to form a guide for the operating link.

One end of the guide is secured to a barrel 49, which is fixed to the usual instrument-board 50 of the automobile. An operating shank 51 is axially movable in this barrel by means of a handle 52. The end of the flexible link is secured to this shank. The shank is axially movable to more or 10 less extent to determine the degree of opening of the valve 24, and is arranged to be secured in adjusted positions by slightly turning the shank in order to place a pin 53 in the barrel selectively in notches 54 15 in the outer face of the wall of the shank, to regulate the amount of heat in the automobile. The flexible guide 48 may at a suitable point be secured to the exhaust-pipe by means of a clip 55.

20 The clamp 28 is arranged to be secured to exhaust-pipes of different diameters. Different automobiles have exhaust-pipes of different diameters, so that this device may be applied to different kinds of automobiles.

25 The two sides of the clamp are arranged to be secured together by means of bolts 57, 58, 59. At the pivot end of the clamp there is a block 61 which forms a separating block between the rear ends of the 30 clamp-sections. It is located between the webs 34 and is part of the wall of the passage 33. The bolt 59 is received through this block and clamps the block and the rear ends of the clamp-sections together. The 35 bolts 57, 58, are received through the flanges 35.

The depending portions of the clamp-sections which are received about the exhaust-pipe extend only partway about the exhaust-pipe and are arranged to be bent or flexed upon arcs of circles of different diameters, corresponding to the diameters of the respective exhaust-pipes, so as to be snugly received against the outer peripheries of said 45 exhaust-pipes. Clamp-bands 63, 64, are employed to clamp the valve-clamp about the exhaust-pipe.

Each of the bands is formed in two sections. The upper ends of these sections are 50 provided with holes 65 through which the bolts nearest to the exhaust-pipe are received, there being one section of each band at each side of the clamp and pipe. The lower ends of these sections are each provided with a series of holes 66, through selective ones of which a bolt 67 is received, a nut 68 together with a bolt 67 clamping the ends of the mating or pair of band-sections toward each other.

60 The sections of a pair of bands are stretched about the depending portions of the clamp and the exhaust-pipe, the lower ends being bent parallel with each other, as shown at 69, so as to place bolt-holes opposite each 65 other to receive the bolt with the bent ends

sufficiently separated to allow the clamping of the band, in order to secure the valve-clamp in place. This arrangement for accommodating different diameters of exhaust-pipes is shown in Fig. 6.

70 One of the bands is provided with a lug 70 for receiving one end of the spring 46.

The valve pivot-stem and valve may be so placed that the extended shank 43 of the valve-stem extends either to the right or 75 to the left, so as to place the operating arm 45 at either the right or the left of the exhaust-pipe, as indicated respectively in full lines and in dotted lines in Fig. 6.

76 The heating element 40 comprises a body section 71, which may be an integral casting, and an upper or cover section 72, which may also be an integral casting and be provided with grooves 73 to prevent slipping thereon. This cover is inside of the automobile. 80 The body section and the cover section are secured together by means of screws 74, a gasket 75 being received in the joint between the two sections. The cover section has a flange 76 around its margin. 85

86 The floor 77 of the automobile is provided with an opening 78 for receiving the depending portion of the heating element, the flange 76 being supported by the wall of the opening and secured to the floor by 90 screws 79, an asbestos gasket 80 being located between said flange and said wall of said opening. All joints in the heating element are on the outside of the automobile.

95 The body section is provided with passages 84, 85. Walls 87, comprising end walls 88, 89, separate the passages 84 from the 100 passages 85.

105 The flexible pipe 38 communicates with an inlet-port 91 of the heating element, being secured in place by means of a set-screw 92. An outlet-port 93 is provided. The outlet-port is shown smaller than the inlet-port to aid in cushioning the impulses of 110 the combustion-exhaust.

115 The walls 87, 88, 89, are shown integral with the body section and projecting toward the cover section, there being a slight space 94 between the upper edges of the walls and the lower face of the cover section. The 120 space 94 is restricted to aid in cushioning the impulses of the combustion-exhaust. The heating element acts as a muffler.

125 The heated gases passing through the inlet-port 91 are received in a cross-passage or manifold 95, which communicates with the lengthwise passages 84. The heated gases of the exhaust then pass through the restricted space 94 at the upper edges of the walls 87, 88, 89, into the passages 85 and the cross-passage or manifold 95, and thence through the restricted outlet-port 93 to the atmosphere. The inlet-port is shown directly communicating with the greater number of 130 passages. The passages 84 are open to the 135

inlet-port, while the passages 85 are open to the outlet-port.

My improved device prevents fumes from reaching the interior of the vehicle; distributes the heat throughout the area of the cover section of the heating element, whence it is distributed throughout the interior of the vehicle; causes the impulses produced by the exhaust and received in the heating 10 element to be cushioned by passing through the restricted space 94 at the upper edges of the walls 87, 88, 89, causing the heating element to act as a muffler, and permitting the exhaust to pass from the receiving manifold 15 and passages to the exhaust passages and manifold and through the outlet-port 93 of restricted area.

The cover section is imperforate to prevent communication between the interior of 20 the vehicle and the heating space in the heating element, and to prevent the lodgment of dirt and moisture in the heating element and consequent deleterious fumes therefrom in the vehicle. The cover section 25 is also preferably made of a material which is light and strong and which readily transmits heat, for instance of a high-grade aluminum. The flexible communicating pipe permits connection with the heating 30 element placed in any suitable position.

I do not herein claim the valve mechanism and means for securing the same, herein shown and described, having shown, described and claimed the same in an application 35 for Letters Patent of the United States on improvements in valves for exhaust pipes of automobiles, Serial No. 702,784, filed March 29, 1924, which is a division of this application.

Having thus fully described my invention, what I claim as new and desire to secure by Letters Patent, is:

1. In a heater for automobiles, the combination of a pair of integral sections having a heating space between them and walls in said space dividing said space into inlet passages and outlet passages having communicating space of restricted area between them, an inlet-port communicating with said 45 inlet-passages, and outlet-port communicating with said outlet-passages, and connecting passage means between said inlet-port and a passage of the automobile for the discharge of the combustion-exhaust.

2. In a heater for automobiles, the combination of a lower integral section, an upper integral cover section, means securing said sections together, said sections having a heating space between them, an inlet-port 50 and an outlet-port for said heating space, connecting passage means between said inlet-port and a passage of the automobile for the discharge of the combustion-exhaust, and walls in said heating space forming channels 55 communicating alternately with said inlet-

port and said outlet-port with openings of large area and intercommunicating space of restricted area between said channels.

3. In a heater for automobiles, the combination of a pair of sections having a heating space between them, an inlet-port and an outlet-port communicating with said space, side walls forming passages, end walls connecting with said side walls at alternate ends of said passages, the opposite ends of 75 said passages being freely open to said respective ports, whereby spaced-apart passages have free communication with said inlet-port and the passages therebetween have free communication with said outlet-port, 80 restricted communicating space between said passages, and connecting passage means between said inlet-port and a passage of the automobile for the discharge of the combustion-exhaust. 85

4. In a heater for automobiles, the combination of a lower integral body-section, an upper cover-section, said lower body-section provided with upwardly extending walls comprising side walls forming passages and 90 end walls alternately located at opposite ends of said passages and connecting with said side walls for forming inlet-passages and outlet-passages, said body-section provided with an inlet-port communicating 95 with said inlet-passages and with an outlet-port communicating with said outlet-passages, means securing said sections together with restricted space between the upper edges of said walls and said upper cover-section, and connecting passage means between said inlet-port and a passage of the automobile for the discharge of the combustion-exhaust. 100

5. In a heater for automobiles, the combination of a lower body-section provided with an inlet-port and an outlet-port, a cross-passage at each of said ports, walls integral with said body-section extending lengthwise between said ports to form passages, end-walls integral with said body-section extending crosswise between said ports and alternately located at opposite ends of said passages, a cover-section received over 110 said body-section, means for securing said sections together with space of restricted area between the upper edges of said walls and said cover-section, and connecting passage means between said inlet-port and a passage of the automobile for the discharge 115 of the combustion-exhaust. 120

6. In a heater for automobiles, the combination with the floor of an automobile, said floor provided with an opening, a lower body-section received in said opening, said body-section provided with an inlet-port, an outlet-port, a cross-passage for each of said ports, walls extending lengthwise between said cross-passages to form lengthwise passages, alternate lengthwise passages 125 130

open respectively to said cross-passage for said inlet-port and said cross-passage for said outlet-port, the opposite ends of said respective lengthwise passages having cross-walls thereacross, said walls integral with said body-section, a cover-plate having its outer margin supported by the wall of said opening, means for securing said cover-section to said body-section with restricted space between the upper edges of said walls and said cover-section, whereby to muffle the exhaust, and connecting passage means between said inlet-port and a passage of the automobile for the discharge of the combustion-discharge.

7. In a heater for automobiles, the combination of a body-section and a cover-section having a heating space therebetween, an inlet-port, a cross-channel at said inlet-port, an outlet-port smaller than said inlet-port, a cross-channel at said outlet-port, walls extending lengthwise between said cross-channels to form lengthwise passages, cross-walls at said respective cross-channels alternately at opposite ends of said lengthwise channels, the greater number of said

lengthwise channels communicating with said inlet-port, said channels having communicating space between them, and connecting passage means between said inlet-port and a passage of the automobile for the discharge of the combustion-exhaust.

8. In a heater for automobiles, the combination of a body section provided with a heating space, a cover section which is imperforate above said heating space, said body section having an inlet-port and an outlet-port, walls in said space to form passages between said ports, a portion of said passages provided with cross-walls adjacent to said inlet-port and another portion of said passages provided with cross-walls adjacent to said outlet-port, and communicating space of restricted area between said passages.

In testimony whereof, I have hereunto subscribed my name in the presence of two subscribing witnesses.

TOM J. SCOTT.
